Claims priority, application Great Britain Oct. 28, 1959
4 Claims. (Cl. 260—397.4)

This invention relates to new steroid compounds, to new processes for the preparation of steroids and to compositions containing the said new compounds. More particularly, it concerns certain new and useful 1-methylgenins, 1-methylene genins and 1-methyl-pregnane derivatives and a new and advantageous process for the preparation of 1-methyl-genins and 1-methyl-pregnane derivatives in general.

Some 1-methyl steroids are already known, but they either contain an aromatic nucleus (the A or B ring) or are derived from the 19-nor series and their preparation in both cases necessitates the transposition of the methyl group from the 10- to the 1-position, or they

10

Soc. 78, 2477 (1956)] and 1-methyl-19-nor-progesterone and its derivatives [Djerassi et coll., J. Am. Chem. Soc. 78, 2479 (1956)], may be obtained by Birch's reduction of the corresponding 1-methyl- $\Delta^{1,3,5}$ -3-alkoxy-estratrienes; and 1-methyl- $\Delta^{1,3}$ -keto-dehydrosteroids, may be prepared by the action of diazomethane on $\Delta^{1,3}$ -keto-dehydrosteroids, followed by pyrolysis of the adduct [as described in German Patent Auslegeschrift No. 1,023,764].

The present invention provides a method of introducing a methyl group into the 1-position of steroids possessing a double bond in the 5-position. The presence of this Δ^5 bond is fundamental, since it can easily be caused to migrate to the 4-position and the majority of physiologically active steroids, such as progestational, androgens, and anti-inflammatories are Δ^4 compounds.

According to a first feature of the invention, there are provided new 1-methyl-steroids and 1-methylene steroids which are the 1-methyl genins of the following general Formulae 1, 2 and 3, the 1-methyl-pregnane derivatives of the following general Formula 4 and the 1-methylene-genins of the following general Formulae 5 and 6:

possess no double bond in the 4- or 5-position. For instance, the 1-methyl- Δ^6 -dehydro-estrogens (described in United States Patent No. 2,671,092) may be prepared by rearrangement of $\Delta^{1,4,6}$ -3-keto-dehydrosteroids by treating the latter with a catalyst capable of producing the dienone-phenol rearrangement; 1-methyl-19-nor-testosterone and its derivatives [Ringold et coll., J. Am. Chem.

70 wherein the various symbols used have the following meanings:

X = O or $(\alpha\text{-H})\beta\text{-OH}$ or $(\alpha\text{-H})\beta\text{-OCOCH}_3$

X' = $(\alpha\text{-H})\beta\text{-OH}$ or $(\alpha\text{-H})\beta\text{-OCOCH}_3$

Y = $-\text{H}$ or $-\text{OH}$ or $-\text{OCOCH}_3$ or Δ^1

Z = $16\alpha,17\alpha$ -epoxy or $16\beta\text{-Br},17\alpha\text{-OH}$ or $16\text{-H},17\alpha\text{-OH}$ or $16\text{-H},17\alpha\text{-OR''}$ or $16\text{-H},17\alpha\text{-H}$ or Δ^{16}

(It will be noted that there is an additional hydrogen atom present in the 16-position, which has not been mentioned in the aforesaid values of Z.)

R' == O or (—H)—OH or (—H)—OCOCH₃
R'' = an acyl group containing up to 9 carbon atoms

derived from a cyclic or non-cyclic aliphatic carboxylic acid or from an aromatic carboxylic acid. (If R'' is derived from a cyclic aliphatic or aromatic acid, the group —CO— which is included may be attached directly to the nucleus or may occur in a side chain and R'' may represent, for example,

Utilising the nomenclature of M. E. Wall and S. Serota [J. Am. Chem. Soc. 79, 6481 (1957)], the spiroketal chain in general formulae 1 and 5 has the configuration 20 α , 22 β , 25D, as in the case of diosgenin, and the spiroketal chain in general Formula 3 has the configuration 20 α , 22 β , 25L, as in the case of yamogenin. In general Formulae 2 and 6 the ethylenic spiroketal chain is the same as in neoruscogenin [J. Robert, R. Vaupre and G. Poiget, C. R. Acad. Sc. 250, 3187 (1960)]. In the general Formulae 1, 2 and 3, a double bond always exists in the 4,5- or 5,6-position and may exist in the 1,2-position. In general Formula 4 a double bond is always present in the 4,5- or 5,6-position and may exist in the 1,2-position and/or the 16,17-position.

The preferred compounds of the invention are the Δ^4 , Δ^5 , $\Delta^{5,16}$ and $\Delta^{4,4}$ derivatives, and more especially 1-methyl-1-hydroxy-diosgenin, 1-methyl-1-hydroxy- $\Delta^{25(27)}$ -dehydrosigenin, 1-methyl-diosgenin, 1-methyl-yamo-

exhibit progestative properties and may be employed in the treatment of the following conditions: primary amenorrhoea, functional dysmenorrhoea, hypo-oligo-menorrhoea, sterility, menorrhagia, habitual abortion, threatened abortion and ovulatory disorders. This progestative activity is particularly pronounced in the case of 1-methyl-17 α -acetoxy-progesterone.

According to a further feature of the invention there is provided a method for the preparation of a 1-methyl-10 1-hydroxy-steroid which comprises subjecting a 1,3-dihydroxy-steroid to oxidation in the 1-position, and reacting the resultant 1-keto-steroid with a metallic derivative of methane.

In a specific application of the foregoing general method the formation of 1-methyl-1-hydroxy-genins, such as 1-methyl-1-hydroxy-diosgenin or 1-methyl-1-hydroxy- $\Delta^{25(27)}$ -dehydrosigenin, is effected by the action of a metallic derivative of methane (also referred to herein as a "Grignard reagent"), such as CH₃MgI, CH₃MgBr or CH₃Li, in an appropriate solvent, either:

(a) On 1-keto-genins having a free hydroxyl group in the 3-position, such as 1-keto-diosgenin or 1-keto- $\Delta^{25(27)}$ -dehydrosigenin, which are prepared by selective oxidation in the 1-position of 1,3-dihydroxy-genins, such as ruscogenin and neoruscogenin (this is shown as route (1), (2) in the flow-sheet set out below), or

(b) On 1-keto-genins having an acetoxy group in the 3-position.

The 3-acetoxy-1-keto-genins are obtained by selective 30 acetylation of 1,3-dihydroxy-genins followed by oxidation in the 1-position or by selective oxidation in the 1-position of 1,3-dihydroxy-genins followed by acetylation in the 3-position (these are shown as routes (3), (4), (5) and (1), (6), (5), respectively, in the following flow sheet).

genin and derivatives of the pregnane series methylated in the 1-position.

The compounds of the foregoing Formulae 1, 2, 3, 5 and 6 are especially useful as intermediates for the preparation of derivatives of 1-methyl pregnanes and in particular those of Formula 4. The compounds of Formulae 1, 2, 3, 5 and 6 can be transformed by the reactions discussed later herein. The compounds of Formula 4, and especially those of the formula:

wherein Y has the significance previously assigned to it and Z' represents a hydrogen atom or a hydroxy or acetoxy group, are physiologically active compounds which

55 The steroids of the pregnane series can be obtained by similar methods. However, in the case of 20 keto-compounds, before proceeding with either of the above routes (1), (2) or (1), (6), (5) it is necessary to block the 20-keto group, for example by forming a cyclic acetal, so that it does not react with the Grignard reagent. Further, if the route (3), (4), (5) is used, it is preferable to reduce the 20-keto group to a secondary alcohol group and then to effect a selective acetylation in the 3- and 20-positions of the 1,3,20-triols obtained before oxidising in the 1-position. It is to be noted that, in the treatment by the above methods of compounds of the pregnane series, a 1-methyl-1,3-dihydroxy-20-keto-pregnane derivative is obtained by using the routes (1), (2) or (1), (6), (5), while a 1-methyl-1,3,20-trihydroxy-pregnane derivative is obtained by using the route (3), (4), (5). It is possible to convert the latter type of derivative to the corresponding 20-keto derivative.

56 As starting materials in carrying out the aforesaid process there may be employed ruscogenin and neoruscogenin which are steroidic sapogenins isolated from *Ruscus aculeatus* L. [H. Lapin, C. R. Acad. Sc. 244, 3065 (1957); Ch. Sannie and H. Lapin, Bull Soc. Chim. 1237 (1957);

J. Robert, R. Vaupre and G. Poiget, C. R. Acad. Sc., 250, 3187 (1960)].

According to a further feature of the invention there is provided a method for the preparation of a 1-methyl-steroid free from a hydroxyl group in the 1-position which comprises acetylating in the 3-position a 1-methyl-1,3-dihydroxy-steroid, dehydrating in the 1-position the resultant 1-methyl-1-hydroxy-3-acetoxy-steroid and hydrogenating the 1-methylene-3-acyloxy-steroid thus obtained.

In a specific application of the above general method for the production of a 1-methyl-steroid free from a hydroxyl group in the 1-position, 1-methyl-genins, such as 1-methyl-diosgenin and 1-methyl-yamogenin, may be prepared by hydrogenation of 1-methylene-genins obtained in a preponderant quantity by dehydration of 1-methyl-1-hydroxy-genins of which the hydroxyl group in the 3-position has been esterified. This may be schematically represented as follows:

In an alternative route, for the preparation of the corresponding 3-hydroxy compound, the hydrogenation step is preceded by saponification of the 1-methylene-3-acetoxy compound. The same series of reactions can be carried out starting from 1-methyl-1-hydroxy-steroids of the pregnane series to produce 1-methyl-pregnane derivatives.

According to a further feature of the invention there is provided a modification of the method set forth above for the preparation of a 1-methyl-steroid free from a hydroxyl group in the 1-position wherein, for the preparation of 1-methyl- $\Delta^{1,4}$ -3-keto-steroids, the said 1-methyl-1,3-dihydroxy-steroid is oxidised in the 3-position and the resultant 3-keto compound is dehydrated.

It will be observed that in the above modification, where the hydroxyl group in the 3-position is oxidised, the dehydration step gives, not the 1-methylene derivative, but the 1-methyl- Δ^1 derivative. And, further, since the dehydration is effected in a strongly acid or strongly alkaline medium, a transposition of the double bond from the 5-position to the 4-position occurs, which permits of directly isolating either the 1-methyl- $\Delta^{1,4}$ -3-keto-genins or the 1-methyl- $\Delta^{1,4}$ -3-keto-pregnane derivatives. As an alternative procedure it is possible to isomerise the said 3-keto compound, by treatment with an acid or alkali, into the corresponding Δ^4 derivative prior to the dehydration step. These procedures are diagrammatically represented as follows:

According to a further feature of the invention there is provided a second modification of the method set forth

above for the preparation of a 1-methyl-steroid free from a hydroxyl group in the 1-position wherein, for the preparation of 1-methyl- $\Delta^{1,4}$ -3-keto-steroids, a 1-methyl-1-acetoxy-3-hydroxy-steroid is oxidised in the 3-position and the 3-keto compound thus obtained is treated with an alkali or acid whereby the elements of an acetic acid molecule are eliminated forming a double bond in the 1,2-position.

The series of transformations in the said second modification set forth above is accompanied by a transposition of the double bond in the Δ^6 -position to the Δ^4 -position and can be diagrammatically represented as follows:

It will be observed that when the 3-keto compound is treated with acid, the product, depending upon the operating conditions, is either a 1-methyl- $\Delta^{1,4}$ -3-keto-steroid or a 1-methyl-1-acetoxy- Δ^{4} -3-keto-steroid. The latter type of compound can be treated with acid or alkali to produce a Δ^1 double bond.

The various processes hereinbefore set forth are illustrated schematically in the accompanying drawings. The five sheets of drawings placed together in the following relative positions:

Sheet 1   Sheet 2

Sheet 3   Sheet 4

Sheet 5

45 constitute a complete flow-diagram showing the various steps in the processes referred to herein. In these drawings the symbol

60 in the case of products having a 20 α ,22 β ,25D spiroketal chain, and these are represented by the letter "a" being placed after the Roman numeral allotted to each compound, or

75 in the case of products having the ethylenic spiroketal chain of neoruscogenin, and these are represented by

the letter "b" placed after the Roman numeral allotted to each compound, or

in the case of products having a $20\alpha,22\beta,25L$ spiroketal chain, and these are represented by the letter "c" being placed after the Roman numeral allotted to each compound. In the formulae of the drawing, the group R'' has the meaning hereinbefore given, and AC represents the acetyl group.

Referring now to the accompanying drawing, the selective oxidation of ruscogenin (Ia) or of neoruscogenin (Ib) to 1-keto-diosgenin (IIa) or 1-keto- $\Delta^{25(27)}$ -dehydrosiogenin (IIb) can be carried out by the oxidation with pyridine/ CrO_3 complex of (Ia) or (Ib), dissolved in pyridine, for about 12 to 24 hours at room temperature and with agitation. It is also possible to effect the oxidation of (Ia) or (Ib), dissolved in an appropriate solvent such as acetone, with an aqueous solution of a mixture of chromic and sulphuric acids and operating at a temperature between -15° and $+20^\circ$ C.

By reaction of 1-keto-diosgenin (IIa) or 1-keto- $\Delta^{25(27)}$ -dehydrosiogenin (IIb) with a Grignard reagent such as methylmagnesium bromide or iodide, in a solvent such as benzene, ether or tetrahydrofuran, or binary mixtures of these solvents, followed by decomposition with acids or an aqueous solution of ammonium chloride, there is obtained 1-methyl-1-hydroxy-diosgenin (Va) or 1-methyl-1-hydroxy- $\Delta^{25(27)}$ -dehydrosiogenin (Vb). The same products (Va) and (Vb) can be prepared by acetylation of (IIa) or (IIb), for example by means of acetic anhydride in pyridine to obtain the corresponding acetates (IVa) and (IVb), which are thereafter reacted with a Grignard reagent. These derivatives (IVa) and (IVb), can also be obtained from (Ia) or (Ib), of which selective acetylation in the 3-position gives the corresponding 3-acetates (IIIa) and (IIIb). The latter two compounds, dissolved in an appropriate solvent such as acetone, are oxidised at a temperature between -15° C. and $+20^\circ$ C. with an aqueous solution of a mixture of sulphuric and chromic acids.

By degradation of 1-methyl-1-hydroxy-diosgenin (Va) or of 1-methyl-1-hydroxy- $\Delta^{25(27)}$ -dehydrosiogenin (Vb) there is obtained 1-methyl- $\Delta^{5,16}$ -pregnadiene-1,3 β -diol-20-one-1-acetate. (VI), which can also be obtained by degradation of the products (XXIXa) and (XXIXb), of which the preparation will hereinafter be described.

The compound (VI), treated with hydrogen peroxide and alkali in methanolic solution, yields the $16\alpha,17\alpha$ -epoxy derivative (VII), which by acetylation with pyridine and acetic anhydride may be transformed into the 1,3-diacetate (IX). This product (IX) can be converted back to compound (VII) by saponification. 1-methyl- $16\alpha,17\alpha$ -epoxy- $\Delta^{1,4}$ -pregnadiene-3,20-dione (VIII) is synthesised from the 1,3-dihydroxy-1-acetate derivative (VII) which is oxidised, in an appropriate solvent such as acetone, with an aqueous solution of a mixture of chromic and sulphuric acids at -15° to $+20^\circ$ C. and treated with alcoholic alkali in order to obtain the Δ^1 double bond.

1 - methyl - $16\alpha,17\alpha$ -epoxy- Δ^5 -pregnen-1,3 β -diol-20-one-diacetate (IX) reacts with hydrobromic acid to yield the bromohydrin (X), in which the bromine is replaced by hydrogen by hydrogenation of (X), in the presence of palladium on charcoal and in the presence of an al-

kaline reagent, such as triethylamine, ammonium acetate or calcium carbonate, to product (XI).

The product (XI) is acylated in the 17-position in the presence of toluene-p-sulphonic acid to give triacyl compound (XII) which is selectively saponified in the 3-position, for example with KHCO_3 , to obtain (XIII) which, dissolved in an appropriate solvent such as acetone, is oxidised at a temperature between -15° and $+20^\circ$ C. with an aqueous solution of a mixture of chromic and sulphuric acids, to give (XIV). Alkali treatment of (XIV) causes the displacement of the double bond from position 5 to position 4, the elimination of the acetoxy group in position 1 with formation of a double bond in position 1 and, at the same time, the saponification of the acyloxy group in the 17-position, to yield 1-methyl- 17α -hydroxy-1,2-dehydroprogesterone (XV).

The acid treatment of (XIV) eliminates the 1-acetoxy group with formation of a double bond in the 1-position, and also causes migration of the double bond in the 5-position to the 4-position. There is thus obtained 1-methyl - 17α - acyloxy - 1,2 - dehydroprogesterone (XVI). The product (XVI) can also be obtained by esterification of the hydroxyl group in the 17α position of (XV), for example by treating it with a derivative of an acid $R''\text{OH}$, such as an anhydride or a chloride, in the presence of toluene-p-sulphonic acid.

Selective acetylation, with acetic anhydride and acetic acid under suitable conditions, is effected on Δ^5 -pregnen-1, $\beta,3\beta,20\beta$ -triol (XVIII), prepared by reduction of Δ^5 -pregnen-1, $\beta,3\beta$ -diol-20-one-1,3 - diacetate (XVII) with LiAlH_4 in a suitable solvent such as tetrahydrofuran or ether, to obtain the 3,20-diacetate (XIX). The product (XVII) [which is prepared from ruscogenin (Ia) or from neoruscogenin (Ib) by acetylation of the hydroxyl groups situated in 1- and 3-positions, degradation of the diacetate and hydrogenation with palladium on charcoal] is known [H. Lapin, Bull. Soc. Chim. 1501 (1957)].

The compound (XIX), dissolved in an appropriate solvent such as acetone, is oxidised at a temperature between -15° and $+20^\circ$ C. with an aqueous solution of a mixture of chromic and sulphuric acids to obtain Δ^5 -pregnen-3 $\beta,20\beta$ -diol-1-one-3,20-diacetate (XX) which is treated with a Grignard reagent, such as CH_3MgI or CH_3MgBr , in a suitable solvent and subsequently decomposed, with an acid or a solution of NH_4Cl , to yield 1-methyl- Δ^5 -pregnen-1, $3\beta,20\beta$ -triol (XXI). By selective oxidation in the 20-position of (XXI), dissolved in an appropriate solvent such as acetone, with an aqueous solution of a mixture of chromic and sulphuric acids and at a temperature between -15° and $+20^\circ$ C., there may be obtained 1-methyl- Δ^5 -pregnen-1, 3β -diol-20-one (XXII) which is further oxidised in the 3-position under the same conditions to give 1-methyl- Δ^5 -pregnen-1-ol-3,20-dione (XXIII), which may be prepared in a single step by oxidation of (XXI) under the above conditions. The product (XXIII) is rearranged to give 1-methyl-1-hydroxy-progesterone (XXIV).

On hydrogenation of the 1-monoacetate of 1-methyl- $\Delta^{5,16}$ -pregnadiene-1,3 β -diol-20-one (VI) in the presence of a catalyst such as palladium on charcoal, there is obtained the corresponding pregnene (XXV) which, dissolved in a suitable solvent such as acetone, is oxidised between -15° and $+20^\circ$ C. by an aqueous solution of a mixture of sulphuric acid and chromic acid to give 1-methyl-1-acetoxy-3,20-dioxo-pregn-5-ene (XXVI).

Treatment in acid medium of (XXVI) produces the migration of the double bond from the 5-position to the 4-position and the elimination of the acetoxy group in the 1-position with formation of the double bond in the 1-position to give 1-methyl-1,2-dehydro-progesterone (XXVIII).

Treatment in alkaline medium of (XXVI) produces the migration of the double bond from the 5-position to the 4-position and the elimination of the acetoxy group in the 1-position with formation of the double bond in the 1-position to give 1-methyl-1,2-dehydro-progesterone (XXVIII),

which can also be prepared from (XXIII) or (XXIV) or (XXVII).

1-Methyl-1-hydroxy-diosgenin (Va) and 1-methyl-1-hydroxy- $\Delta^{25(27)}$ -dehydrosigenin (Vb) can be selectively acetylated in the 3-position to give the corresponding acetates (XXIXa and XXIXb respectively). Dehydration, for example by means of thionyl chloride, of the acetates gives essentially the 3-acetate of 1-methylene-diosgenin (XXXa) and the 3-acetate of 1-methylene- $\Delta^{25(27)}$ -dehydrosigenin (XXXb) which, on catalytic hydrogenation, such as with palladium on charcoal, give the corresponding 1-methyl derivatives (XXXIa and XXXIc). By degradation of these latter compounds, there is obtained 1-methyl-3 β -hydroxy- $\Delta^{5,16}$ -pregnadien-20-one (XXXII), of which the double bond in the 16-position is selectively hydrogenated in the presence of a suitable catalyst such as palladium on charcoal. There is thus obtained 1-methyl-3 β -hydroxy- Δ^5 -pregnen-20-one (XXXIII), which, dissolved in an appropriate solvent such as acetone, is oxidised at a temperature between -15° and +20° C. with an aqueous solution of a mixture of chromic and sulphuric acids, to give 1-methyl- Δ^5 -pregnen-3,20-dione (XXXIV). 1-Methyl-progesterone (XXXV) is prepared from (XXXIV) by causing migration of the double bond from the 5-position to the 4-position by means of an acid or alkaline medium.

Saponification of (XXXa) and (XXXb) gives the corresponding 3-hydroxy derivatives (XXXVIa, XXXVIb) which, on hydrogenation in the presence of a catalyst such as palladium, gives 1-methyl-diosgenin (XXXVIIa) and 1-methyl-yamogenin (XXXVIIc), respectively.

The preparation of 1-methyl-17 α -acetoxy-progesterone (XLVII) from the 3-acetate of 1-methylene- $\Delta^{25(27)}$ -dehydrosigenin (XXXb) may be effected as follows. Degradation of (XXXb) gives 1-methylene-3 β -acetoxy- $\Delta^{5,16}$ -pregnadien-20-one (XXXVIII) which is dissolved in a suitable solvent such as methanol and epoxidised in the 16,17-position, by treatment with hydrogen peroxide under strongly alkaline conditions, to give 1-methylene-3 β -acetoxy-16 α ,17 α -epoxy- Δ^5 -pregnen-20-one (XXXIX). Acetylation of (XXXIX) forms the corresponding 3 β -acetoxy compound (XL) and treatment of the latter in solution in peroxide-free dioxan with an iodine-free solution of hydroiodic acid under oxygen-free conditions causes rupture of the epoxy ring giving 1-methylene-3 β -acetoxy-16 β -iodo-17 α -hydroxy- Δ^5 -pregnen-20-one (XLI). Reduction of (XLI) with Raney nickel and ethanol eliminates the 16 β iodine atom to give 1-methylene-3 β -acetoxy-17 α -hydroxy- Δ^5 -pregnen-20-one (XLII) and acetylation of this compound gives the corresponding 17 α -acetoxy compound (XLIII). Hydrogenation of (XLIII) in the presence of Adams' platinum saturates the 1-methylene group to give 1-methyl-3 β ,17 α -diacetoxy- Δ^5 -pregnen-20-one (XLIV) and by selective saponification of the latter in the 3-position with HCl and methanol there is obtained 1-methyl-3 β -hydroxy-17 α -acetoxy- Δ^5 -pregnen-20-one (XLV). Oxidation of (XLV) with a solution prepared as described in procedure A(ii) which follows gives 1-methyl-17 α -acetoxy- Δ^5 -pregnen-3,20-dione (XLVI) and heating this in acid medium effects transposition of the Δ^5 double bond to the 4-position thus giving 1-methyl-17 α -acetoxy-progesterone (XLVII).

The examples set forth below will serve to illustrate the production of compounds according to the invention. The temperatures are given in degrees centigrade. The following procedures are illustrative of the production of intermediate compounds:

(A) 1-KETO-DIOSGENIN (IIa) FROM RUSCOGENIN (Ia)

(i) 40 grams of ruscogenin dissolved in 400 ml. of pyridine are added to a suspension of CrO_3 -pyridine complex in pyridine (prepared from 40 g. of CrO_3 and 400 ml. of pyridine) with stirring and at room temperature. After 20 hours of stirring the mixture is poured into 3.2 l. of

water. The product is extracted with benzene, the organic extracts are washed with water, dried and evaporated to dryness under vacuum. The residue is crystallised from ethyl acetate. Yield: 12.75 g. of 1-keto-diosgenin (IIa) melting at 220-222°.

(ii) 14 millilitres of an oxidising solution (prepared from 266 g. of CrO_3 , 230 ml. of conc. H_2SO_4 , 400 ml. of water and the resulting solution diluted with water to 1 litre) are added to a solution of 20 g. of ruscogenin in 2400 ml. of acetone with stirring at -15°. After 1.5 minutes, 20 ml. of a 30% aqueous solution of NaHSO_3 are added and after 10 minutes stirring a solution of sodium acetate (13 g. of sodium acetate $3\text{H}_2\text{O}$ and 30 ml. of water) is introduced. The mixture is concentrated to 400 ml. under vacuum and slowly poured into 2 l. of water. The precipitate is filtered, washed with water, dried and crystallised from acetone. Yield: 10.16 g. of (IIa) melting at 218°-224°.

(B) RUSCOGENIN-3-ACETATE (IIIa) FROM RUSCOGENIN (Ia)

A mixture of 140 g. of ruscogenin, 3360 ml. of acetic acid and 560 g. of acetic anhydride is heated for 18 hours at 60°. The solution is evaporated to dryness in vacuo. The crystalline residue is washed with 1 litre of ether, in which the 3-acetate of ruscogenin is scarcely soluble. After filtration, washing with ether and drying of the insoluble matter, there are obtained 49 g. of the first fraction, melting point 228-231°.

The residue obtained by evaporation of the washing ether of the first fraction is agitated for 1 hour with 460 ml. of boiling di-isopropyl ether. The suspension is filtered while hot and the insoluble matter is washed with 100 ml. of di-isopropyl ether.

After drying, there are recovered 17.5 g. of the second fraction, instantaneous melting point 229-231°.

Saponification with alcoholic potassium hydroxide of the residue of evaporation of the diisopropyl ether which has been employed to purify the second fraction permits of recovering 67 g. of ruscogenin, melting point 198-202°.

(C) NEORUSCOGENIN-3-ACETATE (IIIb) FROM NEORUSCOGENIN (Ib)

By proceeding as in the case of ruscogenin, 140 g. of neoruscogenin give:

Neoruscogenin-3-acetate, first fraction: 57 g., melting point 240-245°,

Neoruscogenin-3-acetate, second fraction, recrystallised from isopropanol: 11.4 g., melting point 240-245°.

Saponification by means of alcoholic potassium hydroxide of the residue of evaporation of the mother liquors of the second fraction permits of recovering 75 g. of neoruscogenin, melting point 192-200°.

(D) 1-KETO-DIOSGENIN-3-ACETATE (IVa) FROM (IIa)

A mixture of 12.75 g. of (IIa), 51 ml. of pyridine and 19 ml. of acetic anhydride is shaken over-night at room temperature. The solution is then warmed on a water-bath for 15 minutes and poured into 500 ml. of water. The precipitate is filtered, washed with water and dried. Yield: 14 g. of the acetate (IVa) melting at 192-194°.

(E) 1-KETO-DIOSGENIN-3-ACETATE (IVa) FROM (IIIa)

34 g. of ruscogenin-3-acetate dissolved in 4590 ml. of acetone are treated with 20.4 ml. of the oxidising solution prepared in procedure A(ii) at 13-15° with agitation in a nitrogen atmosphere. The solution is agitated for 4 minutes, whereafter 4590 ml. of water are added thereto. After agitation for 1 hour at 0°, the precipitate is filtered, washed with 50% acetone and dried. There are obtained 32.2 g. of 1-keto-diosgenin-3-acetate melting at 192-194°.

11

(F) 1-KETO- $\Delta^{25(27)}$ -DEHYDRODIOSGENIN-3-ACETATE (IVb) FROM (IIIb)

25 g. of neoruscogenin-3-acetate dissolved in 3375 ml. of acetone are treated with 15 ml. of the oxidising solution prepared in procedure A(ii) at 15° with agitation in a nitrogen atmosphere. The solution is agitated for 4 minutes, whereafter 3375 ml. of water are added thereto. After agitation for a quarter of an hour, the precipitate is filtered, washed with 50% acetone and dried. There are obtained 22.3 g. of 1-keto- $\Delta^{25(27)}$ -dehydriodiosgenin-3-acetate, M.P. 228-232°.

Example 1

1-METHYL-1-HYDROXY-DIOSGENIN (Va) FROM (IIa)

16.96 grams of 1-keto-diosgenin dissolved in 400 ml. of anhydrous benzene are added to a solution of methyl-magnesium iodide in ether (prepared from 40 g. of Mg, 130 g. of CH_3I and 760 ml. of anhydrous ether). The suspension is warmed at 45°-47° for 7 days and then slowly poured into an aqueous solution of NH_4Cl in water (360 g. of NH_4Cl in 1900 ml. of iced water). The organic layer is separated and the aqueous solution is extracted with ether again. The combined organic extracts are washed with water, dried and evaporated to dryness. The residue is dissolved in 150 ml. of benzene and chromatographed on 400 g. of Florisil. 1 methyl-1-hydroxy-diosgenin is eluted with a benzene-ether mixture (1:1). 13.4 grams of (Va) melting at 200° are obtained.

Example 2

1-METHYL-1-HYDROXY-DIOSGENIN (Va) FROM (IVa)

To a solution of CH_3MgI (prepared from 2.9 g. of Mg and 17 g. of CH_3I) in 255 ml. of anhydrous ether is slowly added with gentle boiling a solution of 9.5 g. of (IVa) in 500 ml. of tetrahydrofuran. This addition takes about 1 hour. Ether is distilled off and, during the distillation, tetrahydrofuran is added until the internal temperature rises to 63°. At this point the distillation is interrupted and the mixture is boiled for 15 hours. The suspension is treated with 400 ml. of a 25% aqueous solution of NH_4Cl and, by operating in the usual manner, 5.1 g. of crude 1-methyl-1-hydroxy-diosgenin melting at 195-205° is obtained. After crystallisation from aqueous methanol there is obtained 4.35 g. of pure 1-methyl-1-hydroxy diosgenin (Va) melting at 215-216°.

Example 3

1-METHYL- $\Delta^{25(27)}$ -DEHYDRODIOSGENIN (Vb) FROM (IVb)

To a solution of methyl magnesium iodide (prepared from 3.86 g. of magnesium and 24.85 g. of methyl iodide in 266 ml. of anhydrous ether) there is added slowly a solution of 10 g. of 1-keto- $\Delta^{25(27)}$ -dehydriodiosgenin-3-acetate (IVb) in 350 ml. of anhydrous benzene. The mixture is refluxed for 3 hours, shaken for a further 15 hours at room temperature and then treated with 500 ml. of a 25% aqueous solution of ammonium chloride.

After the usual treatment, the crude product dissolved in benzene is chromatographed on 95 g. of Woelm neutral alumina (activity: 1). A small ketone fraction is eluted by 380 ml. of benzene and then the column is eluted by 950 ml. of ethanol. The alcoholic eluate is evaporated to dryness under vacuum and the residue is recrystallised from a 10% solution of methanol in diisopropyl ether. There is obtained 3.55 g. of 1-methyl-1-hydroxy- $\Delta^{25(27)}$ -dehydriodiosgenin (Vb), melting at 168-176°. The pure product, obtained by crystallisation from ethyl acetate, melts at 192-194°.

Example 4

1-METHYL- $\Delta^{5,10}$ -PREGNADIEN-1,3 β -DIOL-20-ONE-1-ACETATE (VI) FROM (Va)

A mixture of 15 g. of 1-methyl-1-hydroxy-diosgenin (Va), 4.5 g. of monomethylamine hydrochloride, 12 ml.

12

of pyridine and 44 ml. of acetic anhydride is boiled for 2.5 hours. The solution is poured into iced water and extracted with ether after 2 hours. The organic extract is washed with 10% HCl , water, 5% NaHCO_3 and again with water. The ether solution is evaporated to dryness. Yield: 18 g. of thick oil.

The above oil, dissolved in 300 ml. of acetic acid, is treated with an oxidising solution (9 g. of CrO_3 , 15 ml. of water and 60 ml. of acetic acid) at 20° with stirring. The stirring is continued for 75 minutes than 150 ml. of ethanol are added and the solution is again shaken for 1 hour. The solution is concentrated to a small volume, dissolved in 150 ml. of ethanol and poured into 300 ml. of water. The suspension is extracted with ether. The extract is concentrated, after being washed to neutrality, and 16.8 g. of oily product are obtained. The 16.8 g. of the latter product, dissolved in 450 ml. of t-butanol, are allowed to react with 27 g. of KOH dissolved in 36 ml. of water at room temperature for 16 hours with stirring. The solution is extracted with ether. After evaporation of the ether, 9.4 g. of (VI) are obtained as an oily product.

Example 5

1-METHYL- $\Delta^{5,10}$ -PREGNADIEN-1,3 β -DIOL-20-ONE-1-ACETATE (VI) FROM (XXIXa)

A mixture of 10.3 g. of 1-methyl-1-hydroxy-diosgenin-3-acetate (XXIXa) prepared as in Example 22, 3.43 g. of monomethylamine hydrochloride, 10.3 ml. of anhydrous pyridine and 20.6 ml. of acetic anhydride is heated under reflux for 2½ hours (temperature of the heating bath: 160°). The solution is poured into 1 litre of water and extracted with ether. The organic extract is washed with 4% hydrochloric acid, water, 10% potassium bicarbonate and finally water. After drying over sodium sulphate, the ether is evaporated to dryness. Yield: 12.2 g. of a thick yellow oil.

This oil is dissolved in 85 ml. of acetic acid and treated at 15° with agitation with a solution of 3.59 g. of CrO_3 in 72 ml. of acetic acid. The agitation is continued for 1½ hours, whereafter 54 ml. of methanol are added. After having been left over-night at room temperature, the solution is evaporated to dryness in vacuo (20 mm. Hg). The residue is taken up in 100 ml. of ethanol and 90 ml. of water and the suspension obtained is extracted with isopropyl oxide. The extract is washed with water and then with 10% potassium bicarbonate and finally with water. After drying over sodium sulphate, the isopropyl oxide is evaporated to dryness. The residual yellow amorphous product (10.5 g.) is dissolved in 250 ml. of dioxan. The solution is heated under reflux under nitrogen for 2 hours with a solution of 18 g. of potassium hydroxide in 24 ml. of water. After cooling, the dioxan is evaporated in vacuo (20 mm. Hg) and progressively replaced during the distillation by the same volume of water. The residual oil is extracted with ether. The organic extract is washed with 4% hydrochloric acid, water, 10% potassium bicarbonate and finally water. After drying over sodium sulphate, followed by evaporation of the ether, the oily product obtained is chromatographed on silica gel. Elution of the column by a mixture of benzene and ethyl acetate (1:1) gives 1.98 g. of (VI) which, after crystallisation in a mixture of benzene and hexane, melts at 186-187°.

Example 6

1-METHYL- $\Delta^{5,10}$ -PREGNADIEN-1,3 β -DIOL-20-ONE-1-ACETATE (VI) FROM (XXIXb)

By proceeding as in Example 5, using 20 g. of 1-methyl-1-hydroxy- $\Delta^{25(27)}$ -dehydriodiosgenin-3-acetate (XXIXb) prepared as described in Example 23, 3.97 g. of (VI) are obtained, M.P.=183-185°.

13

Example 7

1-METHYL-16 α ,17 α -EPOXY- Δ^5 -PREGNEN-1,3 β -DIOL-20-
ONE-1-ACETATE (VII) FROM (VI)

A solution of 9.4 g. of crude (VI), prepared as described in Example 4 in 150 ml. of methanol is cooled to 8° and treated with 12 ml. of 4 N NaOH and 24 ml. of 33% H₂O₂. After standing at 4° for 4 hours, 2 ml. of acetic acid are added and the solution is poured into 600 ml. of 30% aqueous NaCl. The product is extracted with ethyl acetate, the extract is washed with water and evaporated to dryness. 9.5 grams of (VII) are obtained as an oily product.

Example 8

1-METHYL-16 α ,17 α -EPOXY- Δ^5 -PREGNEN-1,3 β -DIOL-20-
ONE DIACETATE (IX) FROM (VII)

9.5 grams of product (VII) are acetylated with 10 ml. of acetic anhydride and 25 ml. of pyridine at room temperature overnight. The solution is poured into iced water and extracted with ethyl acetate. After evaporation of the solvent, the residue (9.7 g.) is treated with 25 ml. of methanol. 2.75 grams of crude diacetate (IX) melting at 155°-175° are obtained. After crystallisation from methanol, the melting point rises to 173°-177°. There may be recovered from the mother liquors, by chromatography on Florisil, a second crop of 1.5 g. of product (IX) melting at 174-177°.

Example 9

1-METHYL-16 α ,17 α -EPOXY- $\Delta^{1,4}$ -PREGNADIEN-3,20-DIONE
(VIII) FROM (IX)

A solution of 0.81 g. of (IX) in 25 ml. of methanol and 1 g. of KHCO₃ dissolved in 5 ml. of water is boiled for 1 hour. The solution is neutralised with acetic acid, poured into water and extracted with ethyl acetate. The extract, after evaporation of the solvent, yields the crude compound (VII). This product, dissolved in 30 ml. of acetone, is treated, while stirring at -10°, with 0.8 ml. of the oxidising solution prepared in procedure A(ii). After 15 minutes, aqueous NaHSO₃ is added and the mixture is extracted with CH₂Cl₂. After evaporation of the solvent, the residue, dissolved in 20 ml. of methanol, is treated in a nitrogen atmosphere with 0.8 g. of KOH in 1 ml. of water for 5 minutes at boiling temperature. The solution is neutralised with acetic acid, concentrated to a small volume, poured into water, extracted with ethyl acetate; the solvent is evaporated and the residue chromatographed on Florisil. The fraction eluted with benzene is evaporated to dryness and the residue, crystallised from acetone-ether mixture, yields 0.4 g. of (VIII) melting at 208°-210° and showing maximum U.V. absorption at 252 m μ .

Example 10

1-METHYL- Δ^5 -PREGNEN-1,3 β ,17 α -TRIOL-20-ONE-1,3-
DIACETATE (XI) FROM (IX)

4 millilitres of acetic acid saturated with hydrobromic acid (32%) are dropped into a solution of 2.5 g. of 1-methyl-16 α ,17 α -epoxy- Δ^5 -pregnen-1,3 β -diol-20-one diacetate in 12.5 ml. of acetic acid, at 15°. The solution is stirred for 45 minutes at room temperature and then slowly poured into 200 ml. of iced water. The precipitate is filtered, washed with water to neutrality and dried under vacuum at room temperature. The bromohydrin (X) is dissolved in 60 ml. of dioxan and hydrogenated at room temperature and atmospheric pressure in the presence of 0.75 g. of palladium on charcoal and 2.5 ml. of anhydrous triethylamine. When the hydrogenation is over, the catalyst is filtered and the solution is evaporated to dryness. The residue is dissolved in ethyl acetate, the solution is washed with water to neutrality and evaporated to dryness. The crude (XI) is crystallised from acetone-petroleum ether mixture. Yield: 2 g. of (XI) melting at 170-174°.

14

Example 11

1-METHYL- Δ^5 -PREGNEN-1,3 β ,17 α -TRIOL-20-ONE-
TRIACETATE (XII, R''=Ac) FROM (XI)

5 A mixture of 2 g. of (XI), 6 ml. of acetic anhydride and 50 mg. of toluene-p-sulphonic acid is heated to 100° for 1 hour. After cooling, the mixture is poured into iced water and the steroid is extracted with ethyl acetate. The extract is washed with an aqueous 10% NaHCO₃ solution, then with water and then evaporated to dryness. The residue is dissolved in 50 ml. of benzene and chromatographed on 50 g. of Florisil (30-60 mesh). The fractions eluted with benzene and benzene-ether mixture (9:1) are evaporated and the residue is crystallised from ether. Yield: 0.9 g. of pure (XII, R''=Ac) melting at 183-185°.

Example 12

1-METHYL-17 α -HYDROXY-1,2-DEHYDRO-PROGESTERONE (XV) FROM (XII, R''=Ac)

20 A mixture of 0.9 g. of (XII, R''=Ac) dissolved in 25 ml. of methanol and 0.9 g. of KHCO₃ dissolved in 5 ml. of water is boiled for 1 hour. The solution is cooled, neutralised with acetic acid, concentrated to a volume of 10 ml., poured into water and the product is extracted with ethyl acetate. The extract is washed with water and evaporated to dryness. The residue (XIII, R''=Ac) is dissolved in 30 ml. of acetone and the solution is cooled to -10°. 0.9 millilitre of the oxidising solution prepared in procedure A(ii) is added to the prepared solution and the temperature is kept at -10° for another 15 minutes.

25 The excess of CrO₃ is reduced with a solution of sodium bisulphite, the solution is diluted with water and the product extracted with ethyl acetate. The extract is washed with water and evaporated. The residue (XIV, R''=Ac) is dissolved in 20 ml. of methanol and mixed with 0.8 g. of KOH dissolved in 1 ml. of water and the mixture is boiled for 5 minutes in a nitrogen atmosphere. The solution is neutralised with acetic acid and concentrated under vacuum; ethyl acetate is added and the organic solution is washed with water and evaporated.

30 The residue of crude (XV), dissolved in benzene, is chromatographed on 12 g. of Florisil (30-60 mesh). The column is eluted with benzene containing 10% to 25% ether and the fractions are combined and evaporated. By crystallisation of the residue from acetone-ether or acetone-petroleum ether mixture, 450 mg. of pure (XV), melting at 220-224°, are obtained. Maximum U.V. absorption is at 250 m μ .

Example 13

1-METHYL- $\Delta^{1,4}$ -PREGNADIEN-17 α -OL-3,20-DIONE-17-
ACETATE (XVI, R''=Ac) FROM (XIV, R''=Ac)

35 To 0.28 g. of crude 1-methyl- Δ^5 -pregnen-1,17 α -diol-3,20-dione-diacetate (XIV, R''=Ac), dissolved in 25 ml. of ethanol, 2.5 ml. of N H₂SO₄ are added and the mixture is heated for 5 minutes. 0.5 gram of potassium acetate are added and the solution is concentrated to 10 ml. under vacuum. Water is added and the precipitate is filtered, washed with water, dried and crystallised from methanol.

40 95 milligrams of (XVI, R''=Ac), melting at 196°-198°, are obtained. Maximum U.V. absorption is at 251 m μ (ϵ =12,400 in 95% ethanol).

Example 14

(a) Δ^5 -PREGNEN-1 β ,3 β ,20 β -TRIOL (XVIII) FROM (XVII)

To a suspension of 52.4 g. of LiAlH₄ in 1570 ml. of anhydrous tetrahydrofuran are added, at room temperature, 65.5 g. of Δ^5 -pregnen-1 β ,3 β -diol-20-one-1,3-diacetate (XVII) (prepared according to Lapin, loc. cit.) dissolved in 655 ml. of tetrahydrofuran. After the addition, which takes about 70 minutes, the mixture is boiled for two hours. After the usual treatment, the crude product is crystallised from a methanol-water mixture. Yield: 37.5 g. of (XVIII) melting at 259-261°.

15

(b) Δ^5 -PREGNEN-1 β ,3 β ,20 β -TRIOL-3,20-DIACETATE
(XIX) FROM (XVIII)

To a solution of 68.5 g. of triol (XVIII), dissolved in 822 ml. of acetic acid, are added 274 ml. of acetic anhydride and the mixture is warmed at 60° for 3 hours, and then allowed to stand at room temperature for 8 days. The solution is evaporated under vacuum and the oily residue, dissolved in ether, is washed with aqueous 10% KHCO_3 solution, and dried over Na_2SO_4 . After evaporation of the solvent, the residue, dissolved in a benzene-ethyl acetate mixture is stirred with aluminum trioxide for 15 hours, and then the suspension is filtered. The solvents are distilled off under vacuum and the powdery residue is crystallised from methanol. Yield: 43 g. of (XIX) melting at 140°-150°. After crystallisation from a hexane-ethyl acetate mixture, the melting point rises to 158-160° and 26.5 g. of pure (XIX) is obtained.

(c) Δ^5 -PREGNEN-3 β ,20 β -DIOL-1-ONE-3,20-DIACETATE
(XX) FROM (XIX)

17.4 millilitres of the oxidising solution prepared in procedure A(ii) are added at +15°, with stirring and in a nitrogen atmosphere, to 26.5 g. of (XIX) dissolved in 3.57 l. of acetone. The addition takes about 10 minutes, and then the stirring is continued for 4 minutes. The mixture is poured into 17.9 l. of water, and after stirring at room temperature overnight, the precipitate is filtered and washed with water. The crude (XX) is dried and crystallised from isopropyl ether. Yield: 16.8 g. of pure (XX) melting at 101-104°.

(d) 1-METHYL- Δ^5 -PREGNEN-1,3 β ,20 β -TRIOL
(XXI) FROM (XX)

To a solution of CH_3MgI (prepared from 10.8 g. of Mg and 63 g. of CH_3I) in 900 ml. of anhydrous ether are added slowly and with continuous boiling 18.6 g. of (XX) dissolved in 1080 ml. of tetrahydrofuran. The time required for this addition is about 1 hour. Ether is then distilled off with simultaneous addition of tetrahydrofuran, until the internal temperature rises to 63°. Thereafter, the mixture is boiled for 15 hours and then decomposed with 1200 ml. of 25% aqueous NH_4Cl solution. After extraction, evaporation of the solvent and crystallisation of the crude product from ethyl acetate, 10 g. of (XXI) melting at 213-214° are obtained.

Example 15

1-METHYL- Δ^5 -PREGNEN-1,3 β ,20-ONE
(XXII) FROM (XXI)

2.1 grams of (XXI), dissolved in 283 ml. of acetone, are treated with 3.35 ml. of the oxidising solution prepared in procedure A(ii) at +15° with stirring and in a nitrogen atmosphere. The solution is stirred for a further 4 minutes and poured into 1400 ml. of water. After standing for 2 hours in a refrigerator, the precipitate is filtered, washed with water and dried. 0.72 gram of (XXII) melting at 180-185° are obtained. The mother liquors are concentrated and extracted with ether. A second crop of (XXII) is obtained (0.28 g. melting at 185-188°).

Example 16

1-METHYL- Δ^5 -PREGNEN-1-OL-3,20-DIONE
(XXIII) FROM (XXII)

0.72 gram of (XXII) dissolved in 97 ml. of acetone are treated as described in Example 15 with 0.5 ml. of the oxidising solution prepared in procedure A(ii). 0.41 gram of (XXIII) melting at 188-195° are obtained. After crystallisation from methanol the melting point rises to 202-204°.

Example 17

1-METHYL-1-HYDROXY-PROGESTERONE
(XXIV) FROM (XXIII)

A mixture of 0.28 g. of (XXIII), 12 ml. of methanol and 1 ml. of $\text{N H}_2\text{SO}_4$ is boiled for 1 hour. After cooling, the precipitate obtained is filtered and dried. Yield: 0.17 g. of (XXIV) melting at 178-182°. After crystallisation

from ethyl acetate the melting point rises to 188°. Maximum U.V. absorption is at 244 $\text{m}\mu$.

Example 18

1-METHYL-1-ACETOXY-3 β -HYDROXY-20-OXO-PREGN-5-ENE (XXV) FROM (VI)

2.25 grams of 1-methyl- $\Delta^{5,16}$ -pregnadien-1,3 β -diol-20-one-1-acetate (VI) prepared in accordance with Example 5 are hydrogenated under atmospheric pressure and at room temperature in 112 ml. of ethyl acetate in the presence of 2.25 g. of 3% palladium on charcoal. After fixation of 1 mole equivalent of hydrogen, the hydrogenation is stopped. The catalyst is filtered and the solution is evaporated to dryness in vacuo. After crystallisation of the residue from isopropyl oxide, 2.02 g. of (XXV) are obtained, M.P.=189-190°.

Example 19

1-METHYL-1-ACETOXY-3,20-DIOXO-PREGN-5-ENE
(XXVI) FROM (XXV)

0.5 gram of (XXV) dissolved in 21 ml. of acetone are treated at -10° under nitrogen with 0.63 ml. of the oxidising solution prepared in procedure A(ii). The agitation is continued at -10° for 15 minutes, whereafter 2.5 ml. of methanol are added to the solution, which is poured into 100 ml. of water. The precipitate is filtered, washed with water and dried. 0.41 gram of crude (XXVI) is obtained, M.P. 170-174°.

Example 20

1-METHYL-1-ACETOXY-PROGESTERONE
(XXVII) FROM (XXVI)

A solution of 0.5 g. of crude (XXVI) in 39 ml. of methanol, 2.37 ml. of N sulphuric acid and 7.72 ml. of water is heated under reflux for 1 hour. The methanol is evaporated in vacuo. The oil obtained is extracted with ethyl acetate. The organic extract is washed with a 10% aqueous KHCO_3 solution and then with water and dried over sodium sulphate. The solvent is evaporated on the water bath and the residual oil is chromatographed on silica gel. On elution with benzene containing 25% of ethyl acetate, 0.105 g. of pure (XXVII) are obtained, M.P.=136-138°.

Infra-red spectrum (KBr tablet), bands at: 1726 cm^{-1} (ester), 1705 cm^{-1} ($>\text{C}=\text{O}$ in 20-position), 1668 cm^{-1} ($>\text{C}=\text{O}$ in 3-position conjugate), 1612 cm^{-1} (Δ^4).

Ultra-violet spectrum: λ (95% ethanol max.)=245 $\text{m}\mu$, $\epsilon=14,980$.

Example 21

1-METHYL-1,2-DEHYDRO-PROGESTERONE
(XXVIII) FROM (XXVI)

1.32 g. of potassium hydroxide pellets in 1.65 ml. of water is added to a boiling solution of 1.5 g. of (XXVI) in 33 ml. of methanol. Heating under reflux is continued for 5 minutes. The solution, cooled to room temperature, is neutralised by 1.44 ml. of acetic acid, whereafter 21 ml. of water are added thereto. The precipitate is filtered, washed with methanol containing 40% of water and dried. 0.805 gram of (XXVIII) is obtained, which, after crystallisation from methanol containing 20% of water, melts at 147-148° and resolidifies, and melts again at 177-178°. $[\alpha]_D^{20}$ ($c=1$, 95% ethanol)=-32°.

Infra-red spectrum (KBr tablet), bands at: 1699 cm^{-1} ($>\text{C}=\text{O}$ in 20-position), 1658 cm^{-1} ($>\text{C}=\text{O}$ in 3-position conjugate), 1622 cm^{-1} (Δ^4), 1601 cm^{-1} (Δ^1).

Ultraviolet spectrum: λ (95% ethanol max.)=252 $\text{m}\mu$, $\epsilon=18,850$.

Example 22

1-METHYL-1-HYDROXY-DIOSGENIN-3-ACETATE
(XXIXa) FROM (Va)

4.1 g. of (Va) in 8 ml. of pyridine and 4 ml. of acetic anhydride is heated for 1 hour on a water bath. After cooling, the solution is poured into 120 ml. of iced water. The precipitate is filtered, washed with water and dried.

17

4.25 grams of (XXIXa), M.P. 185-190°, are obtained. After recrystallisation from ethanol, the product melts at 197-198°.

Example 23

1-METHYL-1-HYDROXY- $\Delta^{25(27)}$ -DEHYDRODIOSGENIN-3-ACETATE (XXIXb) FROM (Vb)

A solution of 4 g. of (Vb) in 36 ml. of pyridine and 24 ml. of acetic anhydride is heated for 1 hour on a water bath. After cooling, the solution is poured into 300 ml. of iced water. The precipitate is filtered, washed with water and dried. After recrystallisation from ethanol, 2.85 g. of (XXIXb) are obtained, M.P. 222-226°.

Example 24

1-METHYLENE-DIOSGENIN-3-ACETATE (XXXa) FROM (XXIXa)

6 millilitres of thionyl chloride are poured drop-by-drop into a solution of 10 g. of (XXIXa) in 170 ml. of pyridine maintained at 0°. The solution is then agitated for 15 minutes at 0° and then poured into 900 ml. of iced water. The precipitate is filtered, washed with water, dried and recrystallised from ethanol and then from isopropanol. 4.37 g. of (XXXa) are obtained, M.P. 156°.

Example 25

1-METHYL-DIOSGENIN-3-ACETATE (XXXIa) FROM (XXXa)

2 grams of 1-methylene-diosgenin-3-acetate (XXXa) are hydrogenated in 225 ml. of ethanol in the presence of 1.5 g. of 5% palladium on charcoal at room temperature and atmospheric pressure. After fixation of 1 mole equivalent of hydrogen, the hydrogenation is stopped. The catalyst is filtered and the alcoholic liquor distilled to dryness in vacuo.

After repeated recrystallisations of the residue from ethanol, 0.4 g. of (XXXIa) are obtained, M.P. 146-148°, $[\alpha]_D^{22}$ (c.=1, CHCl_3)=-90°.

Example 26

1-METHYLENE- $\Delta^{25(27)}$ -DEHYDRODIOSGENIN-3-ACETATE (XXXb) FROM (XXIXb)

6.9 millilitres of thionyl chloride are poured drop-by-drop into a solution of 11.5 g. of (XXIXb) in 195 ml. of pyridine maintained at 0°. The solution is thereafter agitated for 15 minutes at 0° and then poured into 1 litre of iced water. The precipitate is filtered, washed with water, dried and recrystallised from ethanol. 9.6 grams of (XXXb) are obtained, M.P. 145-155°. The pure product obtained by repeated crystallisations from ethanol melts at 185-187°.

Example 27

1-METHYL-YAMOGENIN-3-ACETATE (XXXIc) FROM (XXXb)

5.7 grams of 1-methylene- $\Delta^{25(27)}$ -dehydrodiosgenin-3-acetate (XXXb) are hydrogenated in 635 ml. of ethanol in the presence of 5.7 g. of 5% palladium on charcoal under atmospheric pressure and at ambient temperature. After fixation of 2 mole equivalents of hydrogen, the hydrogenation is stopped. The catalyst is filtered and the alcoholic liquor is evaporated to dryness in vacuo.

After crystallisation of the residue from isopropanol, 2.81 g. of (XXXIc) are obtained, M.P.=181-183°, $[\alpha]_D^{22}$ (c.=1, CHCl_3)=-90°.

Example 28

1-METHYL- β -HYDROXY- $\Delta^{5,10}$ -PREGNADIEN-20-ONE (XXXII) FROM (XXXIc)

A mixture of 7.13 g. of (XXXIc), 2.38 g. of methylamine hydrochloride, 7.13 ml. of pyridine and 14.26 ml. of acetic anhydride is heated under reflux for 2½ hours. The solution is poured into iced water and extracted with

18

ether. The ethereal extracts are washed with N hydrochloric acid, water, a 10% aqueous solution of KHCO_3 and finally with water. After drying and evaporation of the ether, 7.3 g. of a brown amorphous product are obtained.

This crude product dissolved in 60 ml. of acetic acid is treated with an oxidising solution (2.56 g. of CrO_3 and 51 ml. of 90% acetic acid) at 15° with agitation. The agitation is continued for 1½ hours, 40 ml. of methanol are added and the solution is again agitated for 1 hour. The solution is distilled to dryness in vacuo, the residue is dissolved in 100 ml. of 50% aqueous ethanol and the aqueous alcoholic solution is extracted with diisopropyl ether. The organic extracts are washed with water and then with a 10% aqueous solution of KHCO_3 and finally with water. After drying and evaporation of the solvent, 7.5 g. of an amorphous product are obtained.

The preceding crude product is dissolved in 182 ml. of dioxan. There is added to the solution thus obtained a solution of 5.1 g. of potassium hydroxide tablets in 102 ml. of water and the mixture is heated for 2 hours under gentle reflux. After cooling, the dioxan is distilled in vacuo and progressively replaced during the distillation by the same volume of water. The precipitate which is formed is filtered, washed with water and dried.

4.3 g. of brown product (XXXII) are obtained which, after purification by condensation with Girard's reagent T, followed by crystallisation from ethanol, give pure (XXXII), M.P. 190-193°.

Example 29

1-METHYL- β -HYDROXY- Δ^5 -PREGNEN-20-ONE (XXXIII) FROM (XXXII)

0.35 gram of (XXXII) is hydrogenated at atmospheric pressure and room temperature in 30 ml. of ethyl acetate in the presence of 0.35 g. of 5% palladium on charcoal. The theoretical quantity of hydrogen is fixed in 35 minutes. The catalyst is filtered, the solution is distilled to dryness in vacuo and the residue is recrystallised from ethyl acetate. 0.18 gram of (XXXIII) are obtained, M.P. 189-190°.

Example 30

1-METHYL- Δ^5 -PREGNEN-3,20-DIONE (XXXIV) FROM (XXXIII)

80 milligrams of (XXXIII) dissolved in 10.8 ml. of acetone are treated with 0.06 ml. of the oxidising solution prepared in procedure A(ii) at 15° with agitation and in a nitrogen atmosphere. The solution is agitated for 3 minutes and poured into 54 ml. of water. The precipitate is filtered, washed with water and dried. 60 milligrams of crude (XXXIV) are obtained, M.P. 175-177°.

Example 31

1-METHYL-PROGESTERONE (XXXV) FROM (XXXIV)

65 milligrams of crude (XXXIV) are dissolved in 1.4 ml. of methanol to which a drop of 10% aqueous potassium hydroxide solution has been added. The solution is heated under reflux for 5 minutes and neutralised with a drop of acetic acid, whereafter 1.4 ml. of water is added thereto. The crystalline precipitate is filtered, washed with water, dried and recrystallised from methanol containing 20% of water. 31 milligrams of XXXV are obtained, M.P.=154-156°.

Infra-red spectrum (KBr tablet), bands at: 1705 cm^{-1} ($>\text{C}=\text{O}$ in 20-position), 1675 cm^{-1} ($>\text{C}=\text{O}$ in 3-position conjugate), 1620 cm^{-1} (Δ^4).

Ultra-violet spectrum: λ (95% ethanol max.) = 245 μm , $\epsilon=13,400$.

Example 32

1-METHYLENE-DIOSGENIN (XXXVIa) FROM (XXXa)

8.17 grams of 1 - methylene - diosgenin - 3 - acetate (XXXa), prepared as described in Example 24 are added

19

to a solution of 8.17 g. of potassium hydroxide pellets in 817 ml. of methanol; the mixture is heated to reflux for one hour under nitrogen and with agitation. After cooling the solution 8.17 ml. of acetic acid are added thereto and the mixture is evaporated to dryness under vacuum; the crystalline residue is taken up in 250 ml. of water, the solution filtered and the residue washed with water and then dried over-night under vacuum in the presence of concentrated sulphuric acid.

The crude product is dissolved in 134 ml. of benzene and then chromatographed on a column of silica gel (134 g.). Elution of the column with a benzene ethyl acetate mixture (95:5) leads to the isolation of 5.09 g. of 1-methylene-diosgenin, M.P. 148°-149°, $[\alpha]_D^{20} = -91^\circ \pm 5^\circ$ (c.=1, chloroform).

Example 33

1-METHYLENE- $\Delta^{25(27)}$ -DEHYDRODIOSGENIN
(XXXVIIb) FROM (XXXb)

Following the procedure described in Example 32, but starting with 13.3 g. of 1-methylene- $\Delta^{25(27)}$ -dehydrosigenin-3-acetate (XXXb) (M.P. 145°-155°) prepared as described in Example 26, there is obtained 5.73 of 1-methylene- $\Delta^{25(27)}$ -dehydrosigenin, M.P. 171°-173°.

Example 34

1-METHYL-DIOSGENIN (XXXVIIa) FROM (XXXVIa)

1.33 grams of 1-methylene-diosgenin (XXXVIa) dissolved in 66 ml. of ethanol are hydrogenated in the presence of 2.66 g. of 3% palladium on charcoal under atmospheric pressure and at room temperature. The hydrogenation is stopped after the absorption of 1.4 mole equivalents of hydrogen; the catalyst is then filtered off and the ethanolic solution evaporated to dryness under vacuum.

The crude product is dissolved in 50 ml. of benzene and then chromatographed on a column of silica gel (25 g.). Elution of the column with a benzene-ethyl acetate mixture (9:1) gives 0.63 of 1-methyl-diosgenin, M.P. 125°-130°.

Example 35

1-METHYL-YAMOGENIN (XXXVIIc) FROM (XXXVIIb)

2 grams of 1-methylene- $\Delta^{25(27)}$ -dehydrosigenin (XXXVIIb) dissolved in 100 ml. of ethyl acetate are hydrogenated in the presence of 1.6 g. of 10% palladium on barium sulphate under atmospheric pressure and at room temperature. The hydrogenation is stopped after the absorption of 2.3 mole equivalents of hydrogen; the catalyst is then filtered off and the filtrate evaporated to dryness under vacuum.

The crude product is purified by two crystallisations from ethanol and there is obtained 0.32 g. of 1-methyl-yamogenin, M.P. 177°-178°.

Example 36

1-METHYL-DIOSGENIN ACETATE
(XXXIa) FROM (XXXa)

6.9 grams of 1-methylene-diosgenin acetate (XXXa) are hydrogenated in a mixture of 414 cc. ethyl acetate and 13.8 cc. acetic acid in the presence of 0.69 g. of Adams' platinum at ordinary pressure and temperature; the absorption of hydrogen is very rapid and when it falls to about 2 cc. of hydrogen per minute the hydrogenation is stopped, the volume of hydrogen absorbed then corresponding to about 1.1 molecular equivalents. The duration of the hydrogenation is 45 minutes.

The catalyst is filtered off and the filtrate evaporated to dryness under vacuum. After recrystallisation of the residue from 63 cc. of ethanol there is obtained 4.49 g. of (XXXIa), melting point 147°-149°, $[\alpha]_D^{26} = -92^\circ \pm 2^\circ$ (c.=1, chloroform).

20

Example 37

1-METHYLENE- β -ACETOXY- $\Delta^{5,10}$ -PREGNADIEN-20-ONE
(XXXVIII) FROM (XXXb)

5 A mixture of 77.2 g. of crude 1-methylene- $\Delta^{25(27)}$ -dehydrosigenin acetate (prepared as described in Example 26), 25.7 g. of monomethylaminehydrochloride, 77.2 cc. of anhydrous pyridine and 144.4 cc. of acetic anhydride is heated at the reflux for 2½ hours (at a temperature of 144°). The solution is poured into 2,300 cc. of water and extracted with ether. The organic extract is washed successively with 4% hydrochloric acid, water, with a saturated aqueous solution of sodium bicarbonate and finally with water. After drying over sodium sulphate, the ether is evaporated to dryness. Yield: 85.5 g. of a red-brown oil.

This oil is dissolved in 662 cc. of acetic acid and treated at 15° with agitation with a solution of 28 g. chromic oxide in 563 cc. of 90% aqueous acetic acid; the agitation is continued for 1½ hours and then 402 cc. of methanol are added. After being left over night at ambient temperature the solution is evaporated to dryness under vacuum (20 mm. Hg); the residue is taken up into a mixture of 565 cc. of ethanol and 503 cc. of water and the suspension obtained extracted into diisopropyl ether. The extract is washed successively with water, with an aqueous solution of 10% potassium bicarbonate and finally with water; after drying the extract over sodium sulphate, the diisopropyl ether is evaporated to dryness. Yield: 81 g. of a yellow oil.

30 This oil is dissolved in 810 cc. of acetic acid; the solution obtained is heated at the reflux for two hours and after cooling, the acetic acid is evaporated to dryness under vacuum (20 mm. Hg). The oily residue is dissolved in 1 litre of ethyl acetate; the organic solution is washed successively with water, with an aqueous solution of 10% potassium bicarbonate and finally with water and, after drying over sodium sulphate and evaporation of the ethyl acetate under vacuum, the crude product obtained is chromatographed on silicon gel. Elution of the column with benzene containing 2% ethyl acetate gives 30.7 g. of (XXXVIII), melting at 138°-140°.

Example 38

1-METHYLENE- β -HYDROXY- $16\alpha,17\alpha$ -EPOXY- Δ^5 -PREGNEN-20-ONE (XXXIX) FROM (XXXVIII)

35 A solution of 30.7 g. of (XXXVIII) in 3.07 litres of methanol is treated with 62.5 cc. of 4 N sodium hydroxide and 125 cc. of 33% hydrogen peroxide; the solution is left to stand for 17 hours at about 4°, then filtered to remove a small quantity of insoluble material, and poured into 3.1 litres of water. The resulting crystalline suspension is left to stand for 4 hours at about +4° and then filtered; 24.9 g. of (XXXIX) are obtained, melting point 141°-142°.

Example 39

1-METHYLENE- β -ACETOXY- $16\alpha,17\alpha$ -EPOXY- Δ^5 -PREGNEN-20-ONE (XL) FROM (XXXIX)

40 24.9 grams of (XXXIX) are acetylated with 24.9 cc. of acetic anhydride in 49.8 cc. of anhydrous pyridine by heating at 100° for 1½ hours. The solution is decolorised with 1.5 g. of carbon black, cooled to the ambient temperature and poured into 750 cc. of water; the acetyl derivative precipitates and after filtration 27.5 g. of (XL) are obtained, melting at 130°-132°.

Example 40

1-METHYLENE- β -ACETOXY- 16β -IODO- 17α -HYDROXY- Δ^5 -PREGNEN-20-ONE (XL) FROM (XL)

45 100 cc. of a 57% aqueous solution of hydriodic acid, previously freed from all traces of iodine by agitation for several minutes with 0.5 g. of copper powder, are added all at once to a solution of 10 g. of (XL) in 500 cc. of peroxide-free dioxan and into this mixture is bubbled a light current of nitrogen. 20 minutes after the addition

of the hydriodic acid, 1.5 litres of distilled water are added to the solution and the suspension obtained is extracted with peroxide-free diethyl ether, the operation being conducted under nitrogen. The ethereal extract is washed with water, dried over sodium sulphate and evaporated to dryness; 17 g. of (XLI) are obtained in the form of a brown oil, which may be used directly in the procedure of the following example.

Example 41

1-METHYLENE-3 β -ACETOXY-17 α -HYDROXY- Δ^5 -PREGNEN-20-ONE-(XLII) FROM (XLI)

55 grams of Raney nickel are added to a solution of 17 g. of (XLI) dissolved in 600 cc. of ethanol; the suspension obtained is agitated at ambient temperature in darkness and under nitrogen for 30 minutes. After filtering off the nickel, the ethanol is distilled off to dryness under vacuum (20 mm. Hg) and the residue is crystallised from a mixture of 8 cc. of diethyl ether and 16 cc. of hexane. After filtration 7.77 g. of (XLII) are obtained, melting at 154°-155°.

Example 42

1-METHYLENE-3 β ,17 α -DIACETOXY- Δ^5 -PREGNEN-20-ONE (XLIII) FROM (XLII)

A mixture of 2.95 g. of (XLII), 44 cc. of acetic anhydride and 0.59 g. of toluene-p-sulphonic acid is agitated under nitrogen at ambient temperature for 16 hours. The solution is then poured into 200 cc. of iced water and the steroid which precipitates is filtered off, washed with water, and dried; 3.08 g. of (XLIII) are obtained, melting at 183°-184°. After recrystallisation from an ethyl acetate-hexane mixture (1:3), the pure product melts at 184°-185°, $[\alpha]_D^{24} = -30^\circ \pm 1^\circ$ (c.=1, chloroform).

Example 43

1-METHYL-3 β ,17 α -DIACETOXY- Δ^5 -PREGNEN-20-ONE (XLIV) FROM (XLIII)

1 gram of (XLIII) is hydrogenated at ordinary pressure and temperature in a mixture of 60 cc. of ethyl acetate and 4 cc. of acetic acid in the presence of 0.2 g. of Adams' platinum. The absorption of hydrogen is rapid and when it has fallen to about 0.2 cc. of hydrogen per minute, the hydrogenation is stopped; the volume of hydrogen absorbed then corresponds to about 1.1 molecular equivalents. The duration of the hydrogenation is 25 minutes.

The catalyst is filtered off and the filtrate evaporated under vacuum to dryness; after washing the crystalline residue 4 times with 1.5 cc. of hexane, 0.89 g. of (XLIV) are obtained, melting at 157°-159°; $[\alpha]_D^{24} = -50^\circ \pm 2^\circ$ (c.=1, chloroform).

Example 44

1-METHYL-3 β -HYDROXY-17 α -ACETOXY- Δ^5 -PREGNEN-20-ONE (XLV) FROM (XLIV)

A mixture of 1.57 g. of (XLIV) in 47 cc. of methanol and 0.32 cc. of concentrated hydrochloric acid (d.=1.19) is heated under reflux for 1½ hours. A solution of 0.38 g. of potassium bicarbonate in 47 cc. of water is added to the boiling solution. On cooling to ambient temperature the steroid crystallises and after filtration and drying 1.19 g. of (XLV) are obtained, melting at 197°-199°; $[\alpha]_D^{23} = -60^\circ \pm 1^\circ$ (c.=1, chloroform).

Example 45

1-METHYL-17 α -ACETOXY- Δ^5 -PREGNEN-3,20-DIONE (XLVI) FROM (XLV)

1.12 cc. of the oxidising solution prepared as described above in procedure A(ii) are added under nitrogen and with agitation to a solution of 1.166 g. of (XLV) in 157 cc. of acetone and while maintaining the temperature of the medium at about 15°. The agitation is continued for 5 minutes and the suspension is then diluted with 200 cc. of water which initiates crystallisation of the steroid. After leaving the suspension to stand at about 4° for two

hours, the steroid is filtered off, washed with an acetone-water mixture (1:1) and dried. 0.96 g. of (XLVI) are obtained, melting at 202°-204°.

5

Example 46

1-METHYL-17 α -ACETOXY-PROGESTERONE (XLVII) FROM (XLVI)

A mixture of 0.96 g. of (XLVI), 76 cc. of methanol, 4.6 cc. of N sulphuric acid and 15.3 cc. of water is heated under reflux for 1 hour. A solution of 1.2 g. of sodium acetate in 76 cc. of water is then added to the boiling solution and on cooling to ambient temperature the steroid crystallises. After filtration and drying, 0.82 g. of (XLVII) are obtained, melting at 207°.

15

The pure product obtained on recrystallisation from methanol melts at 214°-215°, it resolidifies and remelts at 226°-227°; $[\alpha]_D^{25} = +81^\circ \pm 1^\circ$ (c.=1, chloroform); U.V. spectrum: λ 95% ethanol max.=244 m μ ; ϵ =15,190.

20

This application is a continuation-in-part of application Serial No. 64,462, filed October 24, 1960, now abandoned.

We claim:

- 1-methyl- Δ^5 -pregnen-1,3 β ,20 β -triol.
- A process for the preparation of 1-methyl-1-acetoxy-3 β -hydroxy- Δ^5 -pregnadien-20-one which comprises reacting a compound selected from the class consisting of 1-methyl-1-hydroxy-diosgenin and the 3-acetate thereof and 1-methyl-1-hydroxy- $\Delta^{25(27)}$ -dehydrodiosgenin and the 3-acetate thereof with acetic anhydride in the presence of a reagent selected from the class consisting of pyridine and a pyridine-monomethylamine hydrochloride mixture, oxidising the triacetyl derivative obtained with a chromic acid-acetic acid mixture and saponifying the resultant compound with an alkali metal hydroxide.
- A process for the preparation of a 1-methyl-3-keto- $\Delta^{1,4}$ -steroid of the pregnane series which comprises oxidising in the 3-position a 1-methyl-1-acetoxy-3 β -hydroxy-steroid of the pregnane series with a reagent selected from the class consisting of an aqueous solution of a chromic acid-sulphuric acid mixture and a pyridine-chromic anhydride complex and reacting the product obtained with a reagent selected from the class consisting of alkali metal hydroxides and strong mineral acids.
- A process for the preparation of a 1-methyl-1,3 β -dihydroxy-20-keto-steroid of the pregnane series which comprises reacting a compound selected from the class consisting of 1 β ,3 β -dihydroxy-20-keto-steroids of the pregnane series and the 1 β ,3 β -diacetates thereof with lithium aluminium hydride, acetylating in the 3- and 20-positions the 1,3,20-trihydroxysteroid thus obtained with acetic anhydride, oxidising in the 1-position the resultant 3,20-diacetoxysteroid with a reagent selected from the class consisting of a chromic acid-sulphuric acid mixture and a pyridine-chromic anhydride complex, reacting the 1-oxo-3 β ,20 β -diacetoxy-steroid thus formed with a methyl magnesium halide, hydrolysing the magnesium complex of the 1-methyl-3 β ,20 β -diacetoxy-steroid so obtained in a weakly acidic medium and oxidising in the 20-position the resultant 1-methyl-1,3 β ,20 β -trihydroxy-steroid with a reagent selected from the class consisting of a chromic acid-sulphuric acid mixture and a pyridine-chromic anhydride complex.
